UNITED STATES PATENT OFFICE.

THOMAS M. PUSEY, OF KENNETT SQUARE, PENNSYLVANIA.

EVAPORATOR.

1,371,115.

Specification of Letters Patent.

Patented Mar. 8, 1921.

Application filed September 18, 1919. Serial No. 324,468.

To all whom it may concern:

Be it known that I, THOMAS M. PUSEY, a citizen of the United States, and a resident of Kennett Square, in the county of Chester and State of Pennsylvania, have invented a new and Improved Evaporator, of which the following is a description.

My invention relates to evaporators and more particularly to an apparatus for evaporating water out of zinc-chlorid or out of acid or alkali solutions or the like.

By the usual methods in evaporating water out of a zinc-chlorid solution for example, the steam resulting from the evaporating operation passes off to the air at atmospheric pressure and is lost. An object of my invention is to provide an evaporating apparatus for the indicated purpose employing a primary evaporator and utilizing the steam resulting from the primary evaporator in a way that it will contribute its heat to the evaporating process in a second or main evaporator.

Again, zinc-chlorid solutions attack the metal of the evaporating vessel and produce small punctures in most of the ordinary metals of which the evaporators are made, thereby in time causing the vessel to leak. My invention has for an important object to provide an evaporator or vacuum kettle in which to evaporate a solution of zinc-chlorid or other solutions containing acid or alkali liable to attack the metal of the kettle and which will evaporate in a partial vacuum and at a temperature below that of steam at atmospheric pressure to thereby furnish an evaporator which can utilize exhaust steam from steam engines or steam at atmospheric pressure which comes from a primary evaporator hereinafter referred to, or to utilize exhaust steam from any other convenient apparatus at or near atmospheric pressure, or utilize hot water.

A further object of the invention is to provide an evaporator or vacuum kettle of the indicated character equipped with a steam jacket so that a body of steam at atmospheric pressure, when the apparatus is in operation, will surround the kettle except at the port lights or windows, the arrangement being such that the steam furnishes heat to evaporate the water out of the solution contained in the kettle and at the same

time acts as a seal to prevent air from leaking into the vacuum kettle through any punctures therein and which would result in a breaking or lessening of the vacuum, the advantage being that steam entering the kettle instead of air will do very much less damage to the value of the vacuum than would be caused by the same volume or amount of air, as it is a well known fact that a given volume or a given weight of air in a high vacuum is many times harder to remove than the same volume or weight of steam in the same vacuum; or in other words, a condenser of a given size or capacity will remove from a high vacuum under certain conditions, one hundred, and sometimes several hundred times, the weight or volume of steam that the same condenser would remove in weight or volume of air under the same or like conditions.

The invention also has for an object to provide an evaporator having an inside partition or sleeve within the vacuum kettle, thereby producing a double wall and forming an annular chamber between the walls, the purpose being to cause the solution of zinc-chlorid to circulate and to prevent uneven or sudden foaming in the main mass of the zinc-chlorid as well as to expedite the evaporation.

A further object of the invention is to provide an evaporator having a heating coil beneath the vacuum kettle and so arranged as to utilize the heat of the water of condensation from the steam jacket surrounding the kettle or utilize hot water coming from any convenient source; and to cause said coil to assist in producing a circulation of the zinc-chlorid or other solution being treated.

The invention also has for an object to provide an evaporating apparatus of the indicated character in which provision is made for facilitating the removal of the kettle and other parts when desired, for inspection of parts, or for the closing of any punctures produced in the kettle by the material being treated, or the making of any other necessary repairs.

The above and other objects as will appear are attained by the novel evaporator and appurtenances hereinafter particularly described and defined in the claims.

Reference is to be had to the accompanying drawings forming a part of this specification, it being understood that the drawings are merely illustrative of one example 5 of the invention.

Figure 1 is a longitudinal vertical section of an evaporating apparatus embodying my invention;

Fig. 2 is a partly sectional plan view as 10 indicated by the line 2—2, Fig. 1.

In carrying out my invention in accordance with the illustrated example, a suitable supporting structure or base 10 is provided on which is a tub 11. Removably supported 15 in said tub and spaced therefrom at all sides thereof is a tank 12 having a top 13 advantageously formed in two sections, the joint of which is indicated at 13^a. Within the tank 12 and spaced a substantial distance 20 from the walls thereof is a vacuum kettle or vessel 14 adapted to hold a quantity of solution to be treated and having a closed bottom 14^a and a closed top 14^b. The relative arrangement of the kettle and tank 12 25 is such as to provide a substantial steam space entirely surrounding the kettle as hereinafter further referred to. The exhaust pipe 15 rises from the top of the kettle 14 and connects in practice with any pump 30 or condenser (not shown) adapted to exhaust the air and steam from the kettle. A vent pipe 16 leads into the pipe 15 and has a valve 16^a adapted to exclude air from the exhaust pipe or admit air thereto to 35 break the vacuum, if desired, in removing the solution from the kettle after the evaporating process has been completed, as hereinafter referred to. The top 13 of tank 12 has windows or port lights 17 fitted in tubular closures 18 extending between the tank top 13 and the kettle top 14^b so that an 40 electric lamp or any other source of light may be suspended above one of said windows that observation of the interior of the 45 kettle may be made through the other of said windows.

For a portion of its height the kettle 14 has double walls, there being a partition 19 extending about the exterior from near 50 the bottom thereof to near the top forming an annular space which is in communication with the interior of the kettle through the series of openings 20, said partition being supported in any suitable manner, there 55 being shown a ledge or ring 21 therefor within the kettle. Some or all holes 20 are controlled by valves 22, the stems 23 of which extend through stuffing boxes 24 on kettle 14 and tank 12, and provided with 60 hand wheels or other operating handles 23^a. The total capacity of the openings 20 approximately regulates the flow from the 65 interior of the kettle to the annular chamber between the partition 19 and the outer wall of the kettle and the capacity is regu-

lated closely by the valves 22 at certain of the openings.

In order to make fluid-tight the riveted joints between the body of the kettle 14 and the top and bottom thereof, a liquid seal is 70 provided at each joint by means of a trough 25 having its lower edge making a liquid-tight connection with the exterior of the kettle 14 and rising above the respective joints, said trough being adapted to hold any 75 suitable sealing, filling or impregnating substance that will prevent ingress of air or steam. Similarly, a liquid-seal is provided extending vertically over the vertical joint 14^c (see Fig. 2) of the overlapped edges of 80 the material of the kettle, there being a strip 26 secured at its vertical side edges in a manner to make a fluid-tight joint with the exterior surface of the kettle at opposite sides of the said joint 14^c, the space between 85 the strip and kettle being closed at the bottom so that said space will hold a sealing, filling or impregnating substance extending the full height of said joint 14^c to make the riveting of the kettle fluid-tight. 90

The tank 12 is provided with a steam inlet 27 which in the present example of the invention has connected thereto a supply pipe 29 having a branch pipe 30 leading thereinto and constituting a steam outlet 95 from an evaporator 28 having a heating coil 28^a, said evaporator 28 being generally of the form usually employed in evaporating zinc-chlorid and the like and here modified and employed by me as a primary evaporator. In my use of the evaporator 28 I provide the same with a closed top 28^b having a steam outlet 31 leading to the atmosphere in addition to and directly above the steam outlet 30. A disk valve 32 is positioned between the outlets 30, 31 and is suspended by a link 34 from a lever 33 or the like for operating the valve so that it may be moved to constitute a closure of either of said steam outlets. The pressure 100 of the steam within the tank will maintain the valve in the raised position closing the outlet 31 but any other suitable means may be provided in addition for positively holding the valve in the raised position. 110

The kettle 14 is provided with a supply pipe 35 connected in practice with a source of supply of the solution to be evaporated. Said pipe leads through the bottom 14^a of the kettle to a suitable height above the 120 liquid level of the kettle and preferably has a downwardly inclined outlet 35^a from which the material escapes into the kettle within the partition 19. Said pipe 35 is provided with a valve 36 below the tub 11, the stem 125 37 of the valve being here shown as having a bevel pinion 38 meshing with a similar pinion 39 on a vertical actuating rod 40 provided with any suitable wheel or other handle. From the bottom of the kettle there 130

leads an outlet pipe 41 which passes through the bottom of the tub 11 and is provided below the tub with a valve 42, the stem 43 of which in the illustrated form has a bevel 5 pinion 44 meshing with a similar pinion 45 on a vertical operating rod 46. Also, the kettle 14 is provided with a vertical overflow pipe 47 which terminates within the partition 19 at the fluid level and extends 10 downwardly through the bottom of the kettle and through the bottom of the tub 11 to a well 48, said overflow pipe being approximately thirty-four feet high in practice so that fluid overflowing into the well 15 48 will not rise in response to the vacuum within the kettle. The pipes 35, 41 and 47 have couplings 49 interposed therein so that the lower portions of said pipes may be uncoupled. I provide a heating coil or coils 20 50 in the tank 12, that is to say, in the steam space surrounding the kettle 14 beneath the latter. One end of each coil connects by a valve 51 with the outlet pipe 41 within the tub 11, the stem 52 of said valve extending 25 advantageously obliquely through the stuffing box 53 provided on the adjacent wall of the tank 12, the stem being provided with a suitable wheel or handle for closing or opening the valve 51. The opposite end 30 of a coil 50 is in the form of a riser 54 extending as at 55 into the side of the kettle 14 to thus communicate with the space between the body of the kettle and the partition 19.

35 To supply a quantity of hot water to the tub 11, a water inlet pipe 56 extends upwardly through the bottom of said tub and in practice may be connected with any convenient source of supply to receive any hot 40 water from other portions of the plant such as otherwise would be allowed to waste. Additions to the water in the tub 11 will result from the water of condensation from the steam in the steam jacket surrounding 45 the kettle. The pipe 56 is provided with a valve 57 the stem 58 of which is provided with any suitable operating means, here shown as having a bevel pinion 59 thereon meshing with a similar pinion 60 on a vertical operating rod 61 provided with a hand-wheel or the like, for turning. The operating rods 40, 46 and 61 terminate adjacent to each other for convenience of operation and terminate adjacent to the outer ends of 55 the valve stems 23 and 52.

An overflow pipe 62 is provided in the tub 11 and extends downwardly through the bottom thereof, said pipe rising within the tank 12 to the desired water level. Surrounding the major portion of the overflow pipe 62 within the tank 12 is a sleeve 63 supported in any suitable manner and spaced from said pipe, the upper end of the said sleeve rising above the top of said pipe, and 65 said sleeve being open at the top and bot-

tom. The overflow pipe 62 and its sleeve 63 are made large enough to carry off the water from the tub 11 after the water has lost its heat, and at the same time they constitute an air vent whereby air may pass out 70 of the steam jacket or into the steam jacket through the top of the sleeve 63 and the overflow pipe without being interfered with by the water passing outward through said pipe. The arrangement furthermore acts as 75 a vent for surplus steam to pass out in case more steam is furnished to the steam jacket than is condensed by the kettle and as air may pass into the steam jacket when steam is not furnished fast enough to keep the 80 jacket full of steam, the jacket thereby is maintained under atmospheric pressure. The space between the sleeve 63 and the overflow pipe 62 is large enough to constitute 85 a water passage and because of the sleeve 85 extending higher than said overflow pipe, it will prevent the hotter upper strata of the water in the tub 11 from passing into the overflow pipe while permitting the cooler water nearer the bottom of the tub to furnish the overflow into the pipe through the lower end of the sleeve. An additional steam and air vent 64 may be provided leading outwardly from the tank 12 near the top as shown at the left of the tank in Fig. 1, 90 said vent pipe 64 having a suitable controlling valve 64a. The space between the tub 11 and the tank 12 will receive water to the level of the water within the tank, since the bottom of the tank is open and preferably 100 rests directly on the bottom of said tub, so that the water in said space surrounding the lower end of the tank will constitute a seal or steam trap preventing escape of steam or ingress of air.

105 The top 28 of primary evaporator 28 is fitted with two port lights or windows 65, 66 above one of which a source of light may be suspended or otherwise arranged to illuminate the interior of said evaporator 110 for taking observations through the other of said port lights. In the kettle 14 and secured to the inner wall thereof is a curved deflector 67 extending across the space between the outer wall or shell of the kettle 115 over partition 19 and downwardly toward the center of the kettle. The steam inlet pipe 29 may be provided with a valve 68 above the branch 30 leading from the primary evaporator 28. The numeral 69 indicates the stem of valve 68 and said stem is of suitable length to extend to a point for 120 convenient operation by the attendant. The several pipes entering the bottom of the tub 11 have lock nuts 70 or other suitable means 125 to prevent leakage. The valve stem 52 is detachably engaged with the valve 51 in any suitable manner so that said stem may be withdrawn when the pipe connections of the kettle 14 are disconnected for removal of 130

the kettle, there being shown for the purpose in the illustrated example a polygonal end 52^a on said stem which in practice is received in a corresponding socket in the valve. In the steam jacket surrounding the kettle 14 is an approximately horizontal annular baffle 71 extending from the exterior surface of the kettle leaving a restricted passage for the steam between the edge of said baffle and the wall of the tank 12, whereby to insure a constant volume of steam below the baffle and surrounding the bottom and lower portion of the kettle for insuring heat to the main body or mass of solution within the kettle. A series of collars or bands 72 preferably in the form of flat rings are disposed edgewise on the exterior of the vacuum kettle 14 and serve to brace and stiffen the same so that the kettle may the better resist atmospheric pressure thereon during the evaporating process and thus the cylindrical shape of the kettle is preserved. The lever 33 may be supported in any suitable manner. It is here shown as fulcrumed on a standard 33^a on the cover 28^b of the primary evaporator.

In evaporating with my improved apparatus the valves 16^a, 36, 42 and 57 are first closed and the condenser or air pump connected with the exhaust pipe 15 is put in operation to exhaust the air in the kettle 14 to produce a partial vacuum therein. When the value or pressure of the vacuum has reached the desired degree, the valve 36 is opened and zinc-chlorid or other solution to be evaporated is thus admitted to the kettle through the pipe 35 until the desired quantity is contained in the kettle. Said valve 36 is then closed. The solution may be supplied through the pipe 35 under the influence of the vacuum in the kettle or it may be positively forced through said pipe. The valve 32 is now raised to close the atmospheric outlet 31 of the primary evaporator 28, thereby causing steam to pass through supply pipe 29 and inlet 27 into the space between the tank 12 and the kettle 14. The valve 68 is also opened to allow exhaust steam from the steam engine or other apparatus of the plant to pass into the supply pipe 29 to the steam jacket or space surrounding the kettle. The valve 57 is also opened, allowing hot water from any connected source of supply to pass through pipe 56 into tub 11. Since the hotter water in tub 11 will tend to remain near the top of the body of water in said tub and the water in giving up its heat to the coil or coils 50 will tend to settle to the bottom of the tub, the colder water will pass upwardly into the lower end of the sleeve 63 and upward therethrough to and into overflow pipe 62 and will discharge through the latter. The valve 51 is opened by turning its stem 52, the valve 42 remaining closed at this time.

The solution in the vacuum kettle 14 may now flow downwardly through the pipe 41, through valve 51 into coils 50 and it will rise in vertical pipes 54 until it has reached the level of the solution in the kettle 14. 70 The steam passing through pipe 29 into the steam jacket will drive the air in the steam jacket out through the sleeve 63 and pipe 62 to the atmosphere and also through pipe 64 and through valve 64^a to the atmosphere. 75 The capacity of the vent pipe 64 will be regulated in practice by valve 64^a. The steam will now heat the vacuum kettle and since the latter is entirely surrounded by steam except at the port lights 17, it will be obvious that all parts of the kettle will be exposed to the steam to receive the heat of the latter and thereby heat the solution. The mass of the solution in the chamber outside of the partition 19 at the lower end of 85 said chamber is small as compared with the mass or volume of the solution within the partition and therefore the solution in said chamber will be heated more quickly, some heat, however, being acquired by the solution within the partition by the heat applied to the bottom of the kettle and this being the case the solution in the external chamber will boil and generate steam causing the solution therein with the steam and the 90 foaming condition produced in the solution to be lighter than a similar column of the solution without the steam and foaming. Finally, steam is generated so fast in the external chamber that the solution will rise 100 by the ebullition and pass over the top of the partition 19 and striking the curved deflector 67, it will be directed downwardly into the solution at the approximate center of the kettle and a circulation of the solution will 105 thus be set up from the kettle through the openings 20 to the external chamber and over the top of the partition 19, against the deflector 67 and be returned to the center of the kettle. The flow through the openings 110 20 is exactly regulated by the valves 22. The hot water in the tub 11 and surrounding the coil or coils 50 as well as the steam surrounding the vertically ranging members 54 of the coils will cause said coils to be 115 heated which will heat the solution therein and generate steam from the solution. Since the column of the solution mixed with steam is lighter in weight than a similar weight of the solution alone, the solution will rise 120 in the pipe or pipes 54 and will pass out therefrom at the upper end into the annular chamber at the exterior of the partition 19, mixing with the solution and boiling over the top of the partition and downwardly to 125 the center of the kettle so that a circulation is set up from the center of the kettle downwardly through the pipe 41 and through valve or valves 51 and coil or coils 50. The steam rising from the solution in the kettle 130

will be continually exhausted through the pipe 15 and the boiling or evaporating process continues until the desired amount of water has been evaporated out of the solution or in other words until the solution has reached the desired density, whereupon valve 42 is opened and the solution in the vacuum kettle is drawn out through pipe 41 under the action of a pump if desired or the solution may be permitted to discharge by gravity by opening valve 16^a.

The condenser or pump connected with pipe 15 may be operated continuously, thus maintaining a vacuum in the kettle 14 at the desired value, and a small stream of the solution may at the same time be permitted to pass through the valve 36 to the kettle and a regulated quantity of the solution allowed to discharge through valve 42 and pipe 41.

20 The boiling action and hence the evaporating process may be arrested at any time by closing the valve 68 of the steam supply pipe 29 and causing the valve 32 to close the steam outlet 30 from the primary evaporator 25 28 thereby permitting steam from said primary evaporator to escape to the atmosphere, the cutting off of the steam from the steam jacket surrounding the kettle 14 serving under these conditions to stop the action 30 of the condenser connected with exhaust pipe 15 by the increasing vacuum produced in the kettle in the absence of the generation of steam therein as will readily be understood.

35 The steam passing to the upper portion of the annular steam jacket surrounding the kettle 14, that is to say, the steam rising between the baffle 71 and the tank 12 will maintain sufficient volume of steam at that 40 portion of the steam jacket and the steam may be permitted to escape in restricted quantity through the vent pipe 64, the water of condensation being permitted to pass downward between the baffle 71 and the tank 45 12 to the tub 11.

Reverting to the circulation of the solution from the interior of the partition 19 outwardly through openings 20 to the annular chamber surrounding said partition and upwardly at the outside of the latter, the result 50 is obtained in addition to producing a circulation that the conversion of the water in the solution into steam is promoted in the external chamber by reason of the lesser 55 mass of the solution contacting with the wall of the kettle and by reason of the greater heating surface to which the solution in said chamber is exposed in rising therein. The regulation of the flow outwardly through 60 the openings 20 will be to permit a flow depending on the rate of evaporation which in turn will depend on the amount of steam supplied to the steam jacket and the value of the vacuum maintained in the kettle.

65 Whenever it is desired to remove the kettle

the nuts 70 on the pipes 35, 41 and 47 are loosened, the couplings in said pipes are disconnected and the valve stem 52 of valve 51 is disengaged from said valve. Provision is made also for disconnecting the valve stems 23 and this may be done in any suitable manner. In the illustrated example, the inner section 23^a has a socket 23^b detachably receiving the outer section of the valve stem permitting the latter to be pulled outward thus separating the valve stem. The top 13 of the tank 12 having been removed by disconnecting the sections at the joint 13^a, the kettle with the secured portions of the pipes 35, 41 and 47 and the coil or coils 50 80 75 75 may be lifted from the tank 12, thereby affording access to the kettle and coils for repair.

It may be well to state that the above-described apparatus has its special usefulness in the manufacture of fiber in which large quantities of zinc-chlorid are used and are soaked from the fiber by water, the same zinc-chlorid being used over and over.

I would state in conclusion that while the illustrated example constitutes a practical embodiment of my invention, I do not limit myself strictly to the mechanical details herein illustrated, since manifestly the same can be considerably varied without departure from the spirit of the invention as defined in the appended claims.

Having thus described my invention, I claim:

1. An evaporator apparatus including an evaporating vessel, a structure in which said vessel is supported, said structure forming a receptacle at the bottom thereof for a fluid heating medium, and circulating means external to said vessel but within said structure and connected with the bottom of said vessel for the downflow of the fluid contents of the vessel and with said vessel above the bottom for the return of the fluid thereto.

2. An evaporator including an evaporating vessel having double side walls forming a chamber surrounding the inner wall and in communication with the interior of the vessel below the liquid level thereof and above said liquid level, a coil below and outside of said vessel, and means to subject said coil to heat, said coil being in communication at one end with the interior of the vessel at the bottom of the latter, and in communication at its other end with said chamber above the bottom thereof to promote circulation of the liquid being evaporated.

3. An evaporator including a tub, a tank having an open bottom, and supported with its lower end approximately at the bottom of the tub, and a closed evaporating vessel within the tank, said tub being adapted to hold a heating liquid and being spaced from the tank so that the liquid in the tub will form a seal for the lower end of the tank

- to prevent egress of steam between the tank and tub and prevent ingress of air to the tank.
4. An evaporator including a tub, a tank having an open bottom and supported with its lower end approximately at the bottom of the tub, and a closed evaporating vessel within the tank, said tub being adapted to hold a heating liquid and being spaced from the tank so that the liquid in the tub will form a seal for the lower end of the tank to prevent egress of steam between the tank and tub and prevent ingress of air to the tank; together with an overflow pipe leading from the tub within the tank and determining the height of liquid in the tub and in the space between the tub and tank.
5. An evaporating apparatus including a tub, a tank supported in said tub, said tub being adapted to hold a body of heating liquid, an evaporating vessel supported within said tank and spaced therefrom to produce a steam jacket surrounding said vessel, means to supply steam to said space, an overflow pipe leading from the tub within the tank, and a guard sleeve surrounding the said overflow pipe and extending above the same said guard being spaced from the overflow pipe and from the bottom of the tub and being open at the top and bottom.
6. An evaporating apparatus including a tub, an open-bottom tank supported on the bottom of the tub, an evaporating vessel within said tank and spaced therefrom to provide a steam jacket surrounding the vessel, said tank having a steam inlet leading to said space and adapted to be connected with a source of steam supply, said tub being adapted to hold hot water and to receive the water of condensation from the steam in the steam jacket, and an overflow pipe leading from said tub to permit the overflow of said water.
7. An evaporating apparatus including a tub, an open-bottom tank supported on the bottom of the tub, an evaporating vessel within said tank and spaced therefrom to provide a steam jacket surrounding the vessel, said tank having a steam inlet leading to said space and adapted to be connected with a source of steam supply, said tub being adapted to hold hot water and to receive the water of condensation from the steam in the steam jacket, and an overflow pipe leading from said tub to permit the overflow of said water; together with means surrounding said overflow pipe and preventing direct entrance of water thereto from the hotter strata of water but permitting entrance to said pipe of water from a point below the water level.
8. An evaporator including an evaporating vessel having double walls at the sides spaced from each other to provide a chamber therebetween, said chamber being open at the top to communicate with the vessel within the inner wall, and being in communication also with the interior of the vessel below the liquid level thereof, and valves controlling the last-mentioned communication and operable from the exterior of the evaporator.
9. An evaporator including an evaporating vessel, a structure surrounding said vessel and spaced therefrom to form a steam jacket therebetween, a discharge pipe leading from said vessel at the bottom to carry off the solution after treatment thereof, a valve controlling said discharge pipe, a coil between the bottom of the vessel and the bottom of said structure and connected at one end with said discharge pipe, and a valve controlling communication between said coil and the discharge pipe, said coil having connection at the opposite end with said vessel above the bottom thereof.
10. An evaporator including an evaporating vessel, a structure in which said vessel is supported, and spaced therefrom to provide a space therebetween, an inlet to said structure to conduct a heating medium thereinto, an inlet pipe leading through the bottom of said structure and through the bottom of said vessel, to supply a charge of solution to said vessel, a discharge pipe leading from said vessel at the bottom through the bottom of said structure, said pipes having detachable couplings interposed therein, below the bottom of said structure, a coil in said structure beneath said vessel, said coil being connected at one end of said discharge pipe and connected at its opposite end with said vessel above the bottom thereof, a valve controlling communication between the discharge pipe and said coil, and a valve stem detachably engaging said valve and controllable from the exterior of said structure for operating the valve or detaching the stem from the valve; together with a removable top on said structure permitting the removal of said vessel upon disconnection of said couplings and said valve stem.
11. An evaporator including an evaporating vessel surrounded by a steam space, a primary evaporator having a steam outlet communicating with said space, a steam outlet to the atmosphere from said primary evaporator and positioned in the top thereof, said second outlet being separated from and in alinement with the first-mentioned steam outlet, and a valve disposed in said primary evaporator between said steam outlets, and adapted to be moved axially to a position closing either of said steam outlets and opening the other.
12. An evaporator including a tub, a tank having an open bottom and supported in the tub with its lower end below the top of said tub, a closed evaporating kettle within said

tank and spaced therefrom to form a steam jacket surrounding said kettle, means to maintain a volume of steam in said jacket, said tub being adapted to hold water of condensation resulting from the steam, and an overflow pipe leading from said tub at the bottom and rising therein to a height to

maintain in the tub a water seal for the tank.
